A. M. Carlsen.

UNITED STATES PATENT OFFICE.

CHARLES J. BROWN, OF RIVER FALLS, WISCONSIN, ASSIGNOR TO BROWN SAFETY LADDER COMPANY, OF RIVER FALLS, WISCONSIN, A CORPORATION.

STEPLADDER WITH AUTOMATIC SPREADING AND BRACING MEANS.

1,331,953.

Specification of Letters Patent.

Patented Feb. 24, 1920.

Application filed January 21, 1919. Serial No. 272,398.

To all whom it may concern:

Be it known that I, CHARLES J. BROWN, a citizen of the United States, residing at River Falls, in the county of St. Croix 5 and State of Wisconsin, have invented a new and useful Stepladder with Automatic Spreading and Bracing Means, of which the following is a specification.

This invention relates to improvements in 10 step-ladders, and the main object is to provide a step-ladder with means which will automatically spread the rear legs of the ladder in a lateral direction as soon as they are spread rearwardly from the body, rails 15 of the ladder, and will likewise gather the legs inward to a parallel position with the rails when the front and rear parts of the ladder are brought together in the usual manner of a folding step-ladder. A second 20 object is to so construct a step-ladder that if any of its rails, rungs or other parts get damaged they may readily be removed and substituted by new ones. A third object is to provide a step-ladder with means for 25 taking up the lost motion or wiggle usually appearing in the upper joint of a step-ladder after it has been used for some time, and which gives an unpleasant and unsafe character to the ladder.

30 These and a few other objects, which will presently be described and pointed out in the claims, are attained by the novel construction and combination of parts illustrated in the accompanying drawing, in 35 which:—

Figure 1 is a perspective rear elevation of the improved step-ladder. Fig. 2 is a side elevation of the ladder with certain brace chains added. Fig. 3 is a rear elevation of 40 the ladder in folded position. Fig. 4 is an enlarged portion of one of the rails and one end of a rung or step, showing clearly how these parts are detachably secured together. Fig. 5 is a top view of the step 45 shown in Fig. 4. Fig. 6 is a right hand end view of the step 14 in its normal position, as in Fig. 4, and the nut 19 in dotted line. Fig. 7 is a detail top view of the joint shown in the lower part of Fig. 1. Fig. 8 is a section on the line 8—8 in Fig. 7. Fig. 9 is an enlarged sectional view on the line 9—9 in Fig. 3. Fig. 10 is an enlargement of the portion encircled by the dotted line 10* in Fig. 3, with the leg 31 omitted.

55 Referring to the drawing by reference

numerals, 10 designates the side rails of the ladder; they are secured with their upper ends in resilient metallic sockets 11, by rivets, or screws, 12, and upon said sockets is secured the top step or cap 13 of the ladder. 60 The rails are further secured together, preferably in parallel position, by a series of rungs or steps, 14, each of which is made of angle-iron turned with one flange near enough into horizontal position to constitute 65 a step, and has each end cut loose as at 15 in Figs. 5 and 6, and bent downwardly at right angles, to form a lug 16; said lug is perforated for a screw 17, which is passed through a washer 18 and the rail 10 and 70 provided with a nut 19, which, being placed in the angle of the angle-iron, is prevented from rotation by the flanges thereof. The other flange stands practically in vertical position and has its projecting end portions 75 20 sharpened and inserted such a distance into the rails as will fully prevent turning movement of the step. 21 shows a broad wooden step which may be inserted wherever so desired, as a shelf for tools, paint-pots and the like, or as a more comfortable step to stand on in the upper part of the ladder. Such extra step or steps may have 80 their ends detachably inserted as at 22 in Fig. 1 so as to be removable in case of repair; they are still firmly held in place by the rails as the latter are drawn tightly 85 against them by the screws 17.

Fitted between the washers 23 at the inward sides of the sockets is a tube 24, 90 through which and the sockets and washers 23 and 25 extends a rod 26, having at one end a head 27 and at the other end threads 28, so as to receive a nut 29 having a handle 30. Pivoted upon said rod, within the sockets 11, are the upper ends of the props or rear legs 31 of the ladder: said upper ends are beveled at the inward sides, as shown at 32 in Figs. 1 and 3, so as to allow the lower ends of the legs to spread laterally when so 100 required.

I employ several means, individually or in combination, as may be desired, for closing, spreading and holding spread the legs of the ladder. The main device for said purpose 105 comprises a horizontal brace 33, composed of two sections, each of which has the outer end pivoted at 34 to one of the legs, while the inner ends are overlapped and pivoted together by a bolt 35, to form an upwardly 110

foldable knee-joint; one of the sections having a lateral lug 36 normally resting in a notch 37 of the other section. On the bolt 35 is secured a bifurcated bracket 37^a, in 5 which is pivoted at 38 the junction of a V-shaped brace 39, whose front ends are secured by the pivots 40 to the rails 10. The pivots 34 and 40 are placed in such positions that when the legs 31 are closed against the 10 rails 10, as in Figs. 3 and 9, the braces 33 and 39 will fold upwardly as in Fig. 3 and be located between the wooden parts of the ladder, that is, will not project forwardly or rearwardly beyond the same. In this 15 position the legs are held against accidental unfolding by turning of the nut 29, which causes the metal sockets 11 to pinch the legs. Turning of the nut is also employed to take up wear of the legs in the sockets, so as to 20 maintain proper steadiness to the joints.

In closing up the ladder it is only necessary to give the joint of the brace 33 a slight upward push and then close the legs against the rails, the lateral closing of the 25 legs is taken care of automatically by the braces 39—33. And in spreading the ladder again for use it is only necessary to push or pull the legs rearwardly; the lateral spreading is caused automatically by the 30 said braces, and after the braces 33 have dropped to horizontal position it is evident that no pressure, laterally, forwardly or rearwardly can cause the legs to fold.

The secondary means used consists of two 35 braces 41, pivoted with their lower ends at 42 to the legs and having their upper ends loosely pivoted on a horizontal bar or rod 43, which is movable up and down between 40 guides 44 and the rear edges of the rails. The folding of this device may also require a light upward push against the bar 43, but if so desired the braces 41 may be normally inclined sufficiently to cause the bar 43 to glide upward when closing pressure 45 is applied to the legs and the rails. When the ladder is being unfolded said braces 41 and bar 43 drop automatically to the lower position, in which they provide good resistance to accidental closing of the rear 50 legs toward the rails; but as they do not spread or close the rear legs laterally they are most serviceable in combination with the braces 33. When the bar 43 is in raised position its reduced ends recede into notches

43^a in the rails, so as to permit the rear legs 55 to be closed to the rails, as shown in Fig. 9.

Chains 45 may also be used to limit the spreading of the rear legs rearwardly from the rails; they are shown only as auxiliary 60 emergency means in case the braces should get out of order. They may also do for very small ladders as the only means for preventing too much rearward spreading of rear legs having the above described clamping means about their upper ends. 65

What I claim is:—

1. In a step-ladder, resilient metallic sockets supporting the uppermost step or cap of the ladder, the rails of the ladder forming front legs and having their upper 70 ends secured in said sockets, and the upper ends of the rear legs of the ladder being pivotally secured in the sockets, a headed rod extending through the sockets and forming the pivots for the rear legs, a thumb-nut at one end of said rod, a spacing tube 75 upon the rod and filling between the two sockets, so as to resist them when the nut is applied to tighten the sockets against the rear legs. 80

2. The structure specified in claim 1, said rear legs having their upper ends beveled at the inward sides, to permit the lower ends of the said legs to be spread laterally, and means for closing and spreading said rear 85 legs laterally and also for moving them toward and away from the body of the ladder.

3. In a step-ladder, the combination with the head piece and rails of the ladder, of two rear legs pivotally secured in the head piece 90 with freedom to spread at the lower ends both laterally and rearwardly, an upwardly foldable knee-jointed horizontal brace pivoted with one end to each rear leg, a V-shaped brace having its arms pivoted one 95 to each of the rails of the ladder and its junction pivotally secured to the knee-joint part of the knee-brace. 100

4. The structure specified in claim 3, and a pair of auxiliary braces having their rearward ends pivoted one to each rear leg, and their forward and normally higher disposed ends pivotally connected to a horizontal bar, and means fixed on the rails for guiding said bar in an up and down movement along the 105 rear edges of the rail.

In testimony whereof I affix my signature.
CHARLES J. BROWN.
